CLAIM

The ornamental design for a display screen with animated graphical user interface, as shown and described.

DESCRIPTION

FIGS. 1-17 are front views of the first to seventeenth images of a display screen with animated graphical user interface showing a first embodiment of our new design;

FIGS. 18-29 are front views of the first to twelfth images of a display screen with animated graphical user interface showing a second embodiment of our new design; and,

FIGS. 30-37 are front views of the first to eighth images of a display screen with animated graphical user interface showing a third embodiment of our new design.

The outermost broken line illustrates an electronic device, which is the environment of the design, and forms no part of

(Continued)

the claimed design. The remaining broken line illustrate a display screen, and forms no part of the claimed design.
